UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,157,784.

Specification of Letters Patent. Patented Oct. 26, 1915.

Application filed December 26, 1911. Serial No. 667,903.

To all whom it may concern:

Be it known that I, DAVID S. KENNEDY, a citizen of the United States, and a resident of Brooklyn, county of Kings, and State of New York, have invented a new and useful Improvement in Typographical Machines, of which the following is a specification.

My invention has reference to typographical machines, such as linotype machines of the general organization represented in Letters Patent of the United States, No. 436,532, to O. Mergenthaler, wherein circulating matrices are released from a magazine in the order in which their characters are to appear in print and then assembled in line together with expanding spacers, the composed line transferred to the face of a mold, the mold filled with molten metal to form a slug or linotype against the matrices which produce the type characters thereon, and the matrices thereafter elevated and returned through a distributing mechanism to the magazine from which they started.

More particularly the invention relates to that class of linotype machines in which a magazine or series of magazines is mounted on a frame which may be shifted upward and downward, as shown in Letters Patent of the United States, No. 859,618, to John R. Rogers, and even more specifically in his application for Letters Patent, Serial No. 624,426, filed May 1, 1911.

The main object of the invention is the provision of means whereby one or more movable magazines may be shifted to and from operative position by power actuated devices, instead of manually as in the said Rogers patent and application. To this end I employ hydraulic apparatus, which is preferably operated by a power-driven member of the machine; and in addition to this generic feature I have devised various details and features of construction which are peculiarly advantageous in the general organization.

In the accompanying drawings I have shown my mechanism and apparatus in preferred form, but obviously many changes and variations may be made therein which will still be comprised within its spirit; and, generally speaking, I desire it to be understood that it is not limited to any specific form or embodiment except in so far as such limitations are specified in the claims.

Referring to the drawings: Figure 1 is a

side view of a portion of a linotype machine having my invention applied thereto; Fig. 2 is a transverse vertical section through the hydraulic pump; and Fig. 3 is a vertical section taken substantially on the line 3—3 in Fig. 2.

Referring to the drawings, the general arrangement of the parts is substantially similar to that illustrated in the before-mentioned Rogers application, No. 624,426. The movable magazines A are mounted in the shift frame B, to which is connected the elevating member C, which in the present instance is in the form of a hydraulic piston mounted in the pressure cylinder D.

The fluid, such as oil, or the like, is forced into the cylinder D beneath the piston C through the pipe E by the pump plunger H, which is reciprocated in the ordinary manner in the pump chamber G. The oil or other fluid is stored in the reservoir R and is drawn therefrom through the pipe F to the chamber G, the pipes E and F being provided respectively with the spring-pressed inlet and outlet valves E¹ and F¹,

in the manner well understood in the art. The pump plunger H receives its reciprocating movement from the eccentric strap H¹ and eccentric H² mounted upon the customary intermediate shaft J, which is constantly rotated as in the ordinary commercial linotype machine. The eccentric H² is loosely mounted upon the shaft J and in immediate proximity to the member J¹, arranged to rotate with the shaft J and capable of longitudinal movement thereon, so that it may be thrown into and out of contact with the member H², thus constituting a friction clutch. The engagement and disengagement of the pump and shaft are controlled from the hand-lever K³ pivoted at K⁴, and connected by the link K² to the clutch lever K, which is pivoted at K⁵ and engages with a circumferential groove in the clutch member J¹, in such manner that the movement of the hand-lever effects or breaks the clutch connection at will.

When the clutch is open the shaft J rotates without effect upon the hydraulic apparatus, and when closed the pump plunger H is actuated to force the fluid into the cylinder D, and thereby the piston C, shift frame B, and magazine or magazines A will be elevated. The return or downward movement of the frame B and magazine or magazines A is effected by

gravity upon relieving the pressure in the cylinder D and permitting the fluid therein to return to the reservoir R. The means for effecting this last result are constituted by a by-pass arrangement now to be described.

The pipe E is connected through an intermediate pipe L with the chamber M, from which in turn the return pipe L¹ leads to the reservoir R. Between the pipe L and chamber M is mounted a spring-seated valve M¹, which in the normal operation of the pump remains closed due to the pressure of its spring. The valve M¹ is provided with a stem M², in position to be engaged by the arm K¹ of the clutch lever K. When the hand-lever K³ is operated to disconnect the clutch member J¹ from the member H², it is swung about its pivot K⁵, and the outer end of the arm K¹ is elevated, thereby lifting the valve M¹ from its normal position. This permits the return of the fluid from the cylinder D through the pipe E, pipe L, chamber M, and pipe L¹, to the reservoir R. The piston C is now free to descend in the cylinder D, and similarly this permits the return movement of the shift frame B and the magazine or magazines A by gravity, when the latter are unlocked in the manner hereafter to be described. The valve M¹ subserves an additional function as a safety appliance or relief valve. The pressure of its spring is ordinarily sufficient to maintain it in its seated or closed condition, but in the event of an obstruction to the shifting of the magazines, or of other undue resistance, the valve M¹ will yield and relieve the strain, notwithstanding the continued operation of the pump plunger H. When the magazine or magazines A are shifted to the desired location, they are registered and retained therein by locking means substantially the same as those described in the before-mentioned Rogers application. These means comprise one or more locking bars N, which enter and engage the locking notches N² upon the shift frame, the bars being normally urged into the locking position by springs N¹. In the present instance, when the magazines are shifted in the manner previously described and reach the proper position, the bars N will be forced into the notches N², which then register therewith, thereby holding the shift frame and magazines firmly against movement. In the event that the pump continues its action after the magazine movement is arrested, so as to cause undue pressure in the cylinder D, the valve M¹ will yield to relieve it in the manner above noted. In order to shift the magazine or magazines to another position, the locking bars N must be first removed from the notches N², and this is effected in substantially the same manner as in the said Rogers application, namely, through the pivoted hand-lever O, link O¹, lever O², link

O³, lever O⁴, link O⁵, arm O⁶, rock shaft O⁷, and arms O⁸, which latter act to retract the locking bars N.

As previously stated, my invention has been herein shown in preferred form, but 70 obviously many changes and variations in its construction and mode of application will suggest themselves to those skilled in the art without departure from its scope.

Having thus described my invention, its 75 construction and mode of operation, what I claim and desire to secure by Letters Patent of the United States is as follows:

1. In a typographical machine, the combination of a magazine, pressure-fluid apparatus acting with a yielding pressure to shift it into and out of operative position, and means for controlling said apparatus. 80

2. In a typographical machine, the combination of a magazine, and pressure-fluid apparatus for shifting it into and out of operative position, the said apparatus including a relief chamber to relieve automatically the pressure in the event of undue resistance offered by the magazine. 85

3. In a typographical machine, the combination of a magazine, pressure-fluid apparatus for shifting it into and out of operative position, and manually operated means for controlling the action of said apparatus, 95 the said apparatus including a relief chamber to relieve the pressure automatically after each operation of said means.

4. In a typographical machine, the combination of a magazine, pressure-fluid apparatus comprising a force pump for shifting the magazine into and out of operative position, a constantly operated member of the machine, and means whereby the force pump may be connected to and disconnected from 100 said member at will.

5. In a typographical machine, the combination of a magazine, pressure-fluid apparatus comprising a force pump for shifting the magazine into and out of operative position, operating means for the force pump, a constantly operated shaft, and means whereby the operating means may be connected to and disconnected from the shaft at 110 will. 115

6. In a typographical machine, the combination of a movable magazine, a locking device therefor, pressure-fluid apparatus for shifting the magazine into and out of operative position, and common means for controlling the operation of both said locking device and pressure-fluid apparatus.

7. In a typographical machine, the combination of a movable magazine, a locking device therefor, a constantly operated member, pressure-fluid apparatus for shifting the magazine, and comprising a pump adapted to be connected to said constantly operated member at will, and manually controlled means to effect both the release of said lock-

ing device and the connection of the pump to the constantly operated member.

8. In a typographical machine, the combination of a magazine, pressure-fluid apparatus for shifting the magazine into and out of operative position, means for throwing said apparatus into and out of action at will, and devices controlled by said means for relieving the pressure of the pressure-fluid apparatus when it is thrown out of action.

9. In a typographical machine, the combination of a movable magazine, a power driven member, and pressure-fluid apparatus to shift the magazine into and out of operative position, together with means to connect and disconnect the said member and apparatus and a device operated thereby to relieve the pressure when the apparatus is disconnected.

10. In a typographical machine, the combination of a movable magazine, a power driven member, pressure-fluid apparatus adapted to be operatively connected thereto at will to shift the magazine into and out of operative position, and conjoint means for disconnecting the said member and apparatus and simultaneously relieving the pressure-fluid pressure.

11. In a typographical machine, the combination of a movable magazine, a power driven member, and pressure-fluid apparatus adapted to be operatively connected thereto at will to shift the magazine into and out of operative position, the said apparatus comprising a reservoir and means whereby the pressure is relieved and the fluid permitted to return to the reservoir upon the disconnection of the pressure-fluid apparatus from the power driven member.

12. In a typographical machine, the combination of a movable magazine, hydraulic

apparatus for shifting it into and out of operative position, a locking device for holding the magazine in its shifted position, and automatic means for relieving the pressure of the hydraulic apparatus when the magazine is locked in position.

13. In a typographical machine, the combination of a movable magazine, pressure-fluid apparatus for shifting it into and out of operative position, and independent means for holding the magazine in its shifted position.

14. In a typographical machine, the combination of a magazine, and hydraulic apparatus for shifting it into and out of operative position, the said apparatus including a relief chamber to relieve automatically the pressure in the event of undue resistance offered by the magazine.

15. In a typographical machine, the combination of a magazine, hydraulic apparatus for shifting it into and out of operative position, and manually operated means for controlling the action of said apparatus, the said apparatus including a relief chamber to relieve the pressure automatically after each operation of said means.

16. In a typographical machine, the combination of a movable magazine, hydraulic apparatus for shifting it into and out of operative position, and independent means for holding the magazine in its shifted position.

In testimony whereof I hereunto set my hand this 20th day of December, 1911, in the presence of two attesting witnesses.

DAVID S. KENNEDY.
